(57) **CLAIM**

The ornamental design for a housing for traffic measuring device with sun visor, as shown and described.

DESCRIPTION

FIG. 1 is a front view of a housing for traffic measuring device with sun visor, showing my new design;

FIG. 2 is a right side view thereof;

FIG. 3 is a top view thereof;

FIG. 4 is an upper left rear perspective view thereof; and,

FIG. 5 is an upper right front perspective view thereof.

A left side view of the housing for traffic measuring device with sun visor is omitted as it is symmetric in appearance to the right side view of FIG. 2.
